SYLVANIA, A CORPORATION OF PENNSYLVANIA

RAILWAY BRAKING APPARATUS

Application filed May 20, 1926. Serial No. 110,365.

Our invention relates to railway braking apparatus, and particularly to apparatus secured to the trackway and adapted to exert a braking action upon the wheels of a railway vehicle.

We will describe one form of apparatus embodying our invention, and will then point out the novel features thereof in claims.

10 The accompanying drawing is a view showing one form of apparatus embodying our invention.

Referring to the drawing, reference characters 1 and 1^a designate the track rails of 15 a railway track, supported on cross ties 2 in the usual manner.

Each of the rails is provided with braking apparatus comprising a pair of longitudinally extending members 3 and 4 located on opposite sides of the rail. Brake bars 3^a and 4^a are connected with members 3 and 4, respectively, and may be moved closer to the rails 1 and 1^a when a braking action is desired. Coil springs 5 are held 25 in position between members 3 and 4 and the associated brake bars 3^a and 4^a by stay bolts 6, and serve to limit the mechanical pressure of the brakes against the wheels to that which the springs transmit.

30 Means are provided for moving the brake bars toward and away from the associated rails. This means is shown as a plurality of drive rods 7 rigidly connected to members 3 and other drive rods 8 rigidly connected to members 4.

35 Drive rods 7 and 8 are pivotally connected at their operating ends to bell cranks 9 and 10 respectively, and these bell cranks are in turn pivotally mounted on a fulcrum bar 13, this bar being rigidly secured to the ties of the trackway. Motion is transmitted to bell cranks 9 and 10 through driving bars 11 and 12. Driving bar 12 is connected to a lever 27 at a point 19; driving bar 11 is connected to a 40 lever 14 at pivot 15. Levers 14 and 27 are fulcrumed at points 16 and 20 on a floating fulcrum bar 21 which carries a turn-buckle 22 for adjusting the throw of the brake bars to compensate for wearing down of the 45

50 brake shoes.

Driving bars 11 and 12 carry, in addition to the bell cranks 9 and 10, bell cranks 32 and 33 which are pivotally connected thereto at points 39 and 40. Bell cranks 32 and 33 are also pivoted on stationary fulcrum bar 13 at points 41 and 42. The short arms or cranks 32 and 33 are connected at pivots 35 and 36 by a loosely mounted link 34, the parts 32, 33 and 34 together forming a lazy jack or lazy jack compensator for transmitting the braking thrust from driving bar 12 to driving bar 11 and thence to the brake bars without placing an appreciable stress upon the motor device.

Braking force is supplied to lever 27 by 55 means of a fluid pressure motor, consisting of a cylinder 24, containing a piston 24^a connected to a piston rod 23. Piston rod 23 transmits energy to lever 27 through pivot connection 17, the operating fluid being supplied to the piston through a pipe 37 or 38 one or the other of which is connected at times to a suitable source of fluid pressure. The cylinder 24 is secured to a flange on a bar 28 by means of bolts 29 and 30. The bar 28 is secured to the cross ties 2 by means of members 31 which are firmly bolted to the ties. The cross ties to which supporting members 31 are secured are shown in the drawing as extending transversely beyond 70 the other ties of the trackway to furnish a simple and convenient means of support for the motor.

It will be observed that the lever 14 is 75 pivoted at point 18 to a link 25 which is, in turn, pivoted to cylinder 24 at point 26. This structure furnishes securing means for the left hand end of floating fulcrum bar 21 but our arrangement of the lazy jack and floating fulcrum bar enables us to dispense 80 with a heavy anchorage for the operating cylinder and other means for receiving the thrust of the operating mechanism.

The mode of operation of our device will 85 be explained on the assumption that the piston in cylinder 24 is at the left hand end of its stroke and that brake bars 3^a and 4^a are in their retracted position, away from the associated rails, as shown in the drawing. 100

The direction of movement of the parts is shown by the arrows.

When fluid pressure is supplied to cylinder 24 through inlet pipe 37, pivot 17 will move to the right (as viewed in the drawing) and point 19 will move to the left, the lever 27 being fulcrumed about pivot 20. Driving bar 12 will move to the left, turning the associated bell cranks 9 and 10 about their pivots on fulcrum bar 13. Driving rod 7 will be actuated to force brake bars 3^a, 3^a toward the rails 1 and 1^a respectively, brake bars 4^a, 4^a being simultaneously pulled toward their respective rails by rods 8. It will thus be seen that the brake bars 3^a and 4^a for each rail will be forced closer together and will engage the wheels of a vehicle occupying the trackway. Driving bar 12 in its movement to the left will turn the bell crank 33 about its pivot 42 so as to transmit force through link 34 and bell crank 32 to the driving bar 11, urging driving bar 11 toward the right. The motion of lever 27 will also apply a direct pull on lever 14, through the floating fulcrum bar 21, tending to rotate lever 14 about pivot 18. But pivot 18 is connected with the cylinder 24 and it will therefore be plain that the entire thrust of the motor device is applied to the brake operating mechanism. The bar 11 in moving to the right will actuated the associate bell cranks 9 and 10 and hence operate the brake bars 3^a and 4^a to the left of the lazy jack mechanism, in the manner already described.

When it is desired to retract the brake bars from the rails pipe 37 will be opened to the atmosphere, and then fluid pressure will be supplied to cylinder 24 through pipe 38 to force the piston to the left and restore the parts to the normal positions wherein they are shown in the drawing.

It will thus be seen that our device renders the use of rigid foundation structure and fixed stops unnecessary because all unbalanced stresses in the operating cylinder are applied to the brake bars and consequently the operating cylinder may be mounted on the ends of the cross ties and the supporting structure need only be strong enough to support the weight of the operating mechanism. The use of the lazy jack compensator in combination with the floating fulcrum bar and associated connections enables us to supply considerably more braking pressure to the brake bars than we would be able to supply without it, using an operating motor of the same dimensions and under the same conditions and also avoids all tendency of the operating mechanism to shift in a direction parallel to the track.

Although we have shown and described only one form of apparatus embodying our invention, it is understood that various changes and modifications may be made

therein within the scope of the appended claims without departing from the spirit and scope of the invention.

Having thus described our invention, what we claim is:

1. In railway braking apparatus, the combination with a section of railway track, of a motor device supported on the ties, a plurality of brake bars carried by the ties, and link mechanism connected between said 75 brake bars and said motor device for operating the brake bars by the motor device without stress between the motor device and the ties.

2. In railway braking apparatus, the combination with the railway ties, of a plurality of brake bars supported thereon, a pair of driving bars for actuating said brake bars, a motor device operatively connected to said driving bars, and a lazy jack compensator connecting said driving bars. 80

3. In railway braking apparatus, a plurality of oppositely disposed brake bars, a plurality of driving bars for said brake bars, a motor device for actuating said driving bars, and a lazy jack compensator connecting the adjacent ends of said driving bars. 85

4. In railway braking apparatus the combination with a section of railway track, of a plurality of movable brake bars mounted thereon, a stationary fulcrum bar mounted adjacent to the track rails and having a plurality of bell cranks pivotally mounted thereon, a plurality of movable driving bars secured to said bell cranks, a motor device including mechanical means for operating said driving bars, and means including a lazy jack compensator for transferring the entire operating thrust of the motor device to the 95 brake bars. 100

5. A railway track brake apparatus comprising a plurality of oppositely disposed brake bars movably mounted adjacent to the track rails, a pair of driving bars connected to said brake bars, operating means for said 110 brake bars including a piston and a cylinder, the cylinder being connected to one of said driving bars and the piston to the other, and mechanical means connected between the driving bars for transmitting the thrust from both the live end and the dead end of said cylinder to the brake bars. 115

6. A railway track brake apparatus comprising, a railway track section a plurality of oppositely disposed brake bars mounted adjacent to the track rails, operating means for the brake bars including a cylinder and a piston, two driving bars each having an operating lever, one lever being connected to the cylinder and the other to the piston, a floating fulcrum bar pivotally connected between the operating levers of the driving bars, and mechanical means connected to the driving bars for transmitting the entire 120 op- 125 130

erating thrust of the cylinder and piston to the brake bars.

7. A railway track brake apparatus comprising, a section of railway track, brake bars movably mounted on opposite sides of each rail, a motor device, and link and lever mechanism for moving said bars without creating stress between the motor device and its support.

10 8. A railway track brake apparatus comprising, a section of railway track, a plurality of oppositely disposed brake bars movably mounted adjacent to the track rails, a fulcrum bar secured to the track and carrying a plurality of pivotally mounted bell cranks, two driving bars pivotally mounted on said bell cranks, a motor device for operating said driving bars and a lazy jack loosely connected to one end of each of said driving bars and to the fulcrum bar for transmitting the operating thrust of the motor device to the brake bars.

15 9. A railway track brake apparatus comprising, a section of railway track, a plurality of oppositely disposed brake bars movably mounted adjacent to the track rails, two driving bars pivotally mounted in operative relation to the brake bars, a motor device comprising a cylinder and a piston, a lever connected to each of said driving bars one lever also being connected to the cylinder and the other to the piston, a floating fulcrum bar pivotally connected with each of said levers and a lazy jack pivotally connected to each of said driving bars for transmitting the action and re-action of the motor device to the brake bars.

20 10. A railway track brake apparatus comprising, a plurality of oppositely disposed brake bars, driving bars connected to said brake bars, a single pneumatic cylinder having a piston therein, a pivoted link connecting the cylinder and one driving bar, a pivoted link connecting the piston and another driving bar, and means loosely mounted between said pivoted links for adjusting the throw of said brake bars.

25 11. A railway track brake apparatus comprising, a plurality of oppositely movable brake bars, means for actuating said bars, and mechanical means for transmitting the entire thrust of the actuating means to the brake bars without creating stress between said actuating means and its support.

30 55 12. A railway track brake apparatus comprising, a plurality of oppositely movable brake bars, a pair of driving bars connected to said brake bars, operating means for said driving bars including a single cylinder and a piston, the cylinder being connected to one driving bar and the piston to the other, and means connected to the driving bars for transmitting the action of the piston to the 60 65 brake bars moving in one direction and the

reaction of the cylinder to the brake bars moving in the other direction.

70 13. In railway track brake apparatus, the combination with a plurality of movable brake bars, and a motor for actuating them, of a floating fulcrum bar and a lazy jack compensator connected between the motor and the brake bars for transmitting the operating thrust of the motor to the brake bars.

75 14. In railway braking apparatus the combination with a plurality of movable brake bars and means for actuating them, of means including a lazy jack for transmitting the entire operating thrust of the actuating means to the brake bars.

80 15. A railway track brake apparatus comprising two brake bars located on opposite sides of a track rail, two movable driving bars each connected with both said brake bars, a motor device comprising a cylinder and piston, and mechanical means connecting said cylinder with one driving bar and connecting said piston with the other driving bar in such manner that operation of the motor device urges both said brake bars 90 toward the associated track rail.

85 16. A railway track brake apparatus comprising two brake bars located on opposite sides of a track rail, two driving bars each having an operating lever, a motor device 95 comprising a cylinder connected with one operating lever and a piston connected with the other operating lever, a floating fulcrum bar connecting said operating levers, and means for connecting each driving bar with both brake bars in such manner that actuation of the driving bars by the motor device moves both brake bars toward the associated rail.

100 105 In testimony whereof we affix our signatures.
